UNITED STATES PATENT OFFICE.

KARL E. PEILER, OF HARTFORD, CONNECTICUT, ASSIGNOR TO HARTFORD FAIRMONT COMPANY, OF CANAJOHARIE, NEW YORK, A CORPORATION OF NEW YORK.

MAGNETIC-CLUTCH-CONTROLLING METHOD AND APPARATUS.

1,297,236.

Specification of Letters Patent. Patented Mar. 11, 1919.

Application filed December 16, 1915. Serial No. 67,103.

To all whom it may concern:

Be it known that I, KARL E. PEILER, a citizen of the United States, residing at Hartford, in the county of Hartford and State of Connecticut, have invented new and useful Improvements in Magnetic-Clutch-Controlling Methods and Apparatus, of which the following is a specification.

This invention relates to electromagnetic 10 clutches provided with magnet and armature members of some description, which in operation alternately seize and release each other, the magnet being adapted to have a definite holding power, so as to release whenever the 15 weight or pressure or tension of the load carried, or other work done by the magnet exceeds the attractive force between the magnet and its armature, and forcibly separates them. When the magnet and armature are 20 brought together, an appreciable length of time, varying inversely to the strength of the electric energy employed, is required for building up the attractive power of the magnet to its full holding strength, or to the 25 strength needed for promptly seizing its armature and overcoming the inertia of the latter and its connected parts. Hence when these parts are heavy, or their movements extended; or when the magnet operations are 30 repeated in rapid succession, an electric current, sufficient for the required ultimate holding force of the magnet, may be insufficient to cause the magnet to seize and move its armature with sufficient rapidity and cer- 35 tainty. This retardation in building up the attractive power of the magnet is sometimes termed "magnetic lag." The practical effect is that the immediate seizing capacity of a magnet, using a given current is not equal 40 to the ultimate holding capacity of the same magnet under the same current.

The object of this invention is to provide for controlling magnetic clutches under such conditions, varying the electric energy supplied to the magnet to adapt its seizing and holding powers to its required functions, in properly timed relation to the performance of those functions.

Among the uses for which these magnetic 50 clutches are employed, may be instanced that of the pressing of glassware, in which it is

desirable to discontinue the pressure upon the plastic glass just when the latter completely fills the mold into which it is pressed, at which point the increasing resistance of 55 the glass overcomes the holding power of the clutch and forcibly separates its magnet and the armature members, the latter, after each releasing operation being brought together again for the succeeding pressing operation. 60

It will be understood that this invention may be employed for rotative movements, as for instance in a rotary or oscillatory clutch, as well as for the longitudinal reciprocating movements illustrated in the accompanying 65 drawings, which show an embodiment of the invention in a simple type of apparatus.

Figure 1 of the drawings is a side elevation, showing simple elements of a press in which, in this case, the press head or ram 70 operates in a downward direction. Fig. 2 is also an elevation projected from a portion of Fig. 1. Fig. 3 is an elevation showing the clutch of Fig. 1 in its released condition. Fig. 4 is an elevation showing a modified ap- 75 plication of the invention to a press head or platen operated in an upward direction. It will be understood, however, that the movements may be directed or translated in any desired direction. 80

In the embodiment illustrated in Figs. 1, 2 and 3, a column or frame 5 supports a ram 6 for vertical sliding movement, the lower end of the ram being provided with any well-known chuck or socket for holding any 85 desired punch or plunger, or other tool, thus enabling different implements to be substituted at will. A lever 7 pivoted at 8 to the frame, is connected to the ram in any ap- 90 proved way, the connection here shown be- 95 ing a toothed rack and sector pinion. Toward the other end of the lever, it is pivot- ally connected to the armature 10 of the magnet 11, by means of sliding blocks 12 fitted in the arms 13 and 14 of the lever 7, and turning upon pivot studs 15 fixed to the sleeve 16 of the armature, the latter being fitted to slide freely upon the operating rod 17, which in turn is mounted to slide verti- 100 cally in the bosses 18 of the frame or column 5. The operating rod 17 is moved longitudinally to the extent and at the time re-

quired for the operations of the ram 6, by means of a crank or cam, or other well-known driving member. In the present instance, the rod is driven by a cam 20 adjustably secured to the shaft 21 by means of a set screw 22, and bearing against the friction roller 19 mounted in the rod. At the upper end of the rod 17 or at any desired portion of its length is secured the magnet 11, by means of a nut 23 or other suitable means. The magnet is electrically connected to its energizing circuit, by means of flexible leads 24, to allow of the desired movement of the magnet. The magnet is here shown to be energized by a battery 25 in the circuit 26, which is also preferably provided with a switch 27. In the circuit is also installed a rheostat 28, which may be adjusted to vary the strength of the magnet. Shunting the rheostat 28 is a circuit 30 having brush terminals 32, through which the shunt circuit is closed by contacting with a moving conductor sector 33 carried by the insulating disk 34 adjustably fixed on the cam shaft 21, or connected to some other shaft driven in suitable relation therewith. In cases wherein it is desirable to vary or adjust the seizing power of the magnet, or the rapidity of building it up to a given power, another rheostat 31 is included in the circuit, as shown in Fig. 1. The shunt circuit 30 is closed by the sector 33 just before the magnet picks up or engages with its armature, and the rheostat 31 is adjusted to suit that operation, while the other rheostat 28 is adjusted to suit the current required through the circuit 26 to energize the magnet up to the strength or pull at which it is desired to release the armature.

In the operation of this device, the rotations of the cam 20 move the rod 17 and its connected magnet 11 longitudinally through the desired length of stroke, the armature 10 when engaged by the magnet moving the lever 7 and its connected ram 6 to the desired extent. The strength of the magnet for its seizing function is regulated by the rheostat 31 until the armature with its connected parts are picked up with unfailing certainty. The sector 33 closes the circuits a little in advance of the time when the magnet reaches the bottom of its stroke, and makes contact with its armature. After the magnet has firmly seized its armature and has started the parts in motion, the sector 33 leaves the brushes 32, thus opening the circuit 30, leaving the magnet 11 connected in the circuit 26, the rheostat 28 of which is adjusted to allow the passage of current sufficient to produce in the magnet the exact amount of holding power which is to be overcome by the work done by the ram. As soon as the ram 6 encounters in its work a resistance which overcomes the holding

power of the magnet, the latter pulls away 65 from its armature, and completes the stroke imparted by its cam 20, returning later to reengage the armature as above described.

By this regulation of the magnet it may be worked at high speed or at high pressure, 70 or both, and the power of the magnet may be varied to suit a wide range of difference in speed of operation as well as in the holding power required for its releasing and seizing functions. 75

In the modification shown in Fig. 4 the magnet 40 and its operating rod 41 are or may be similar to that shown in the preceding figures, and may be operated by the same or similar mechanism. The modification is mainly in the mounting and connection of the armature 42, which is here shown as part of a cross head or slide 43 mounted upon rods 44, which may be employed as fixed guide rods, for guiding the movement of the cross head, or may be employed as connecting rods to which the armature is secured for transmitting the movement of the armature to a more distant point. The upper portion of the slide 43 is here shown 90 to be provided with a seat or socket 45 for receiving any desired form of chuck, plunger, platen, or other implement suited to the work to be done.

In various ways within the knowledge of 95 those skilled in this art, this invention may be modified to adapt it to different kinds of work or to different types of mechanism.

I claim as my invention:—

1. The method of regulating the strength 10 of a magnetic clutch, which consists in varying the electrical energy supplied to the magnet in timed relation to the work of the clutch.

2. The method of regulating the strength 10 of an electromagnetic clutch, to adapt it to different loads, which consists in varying the electrical energy supplied to the magnet in timed relation to the occurrence of the said loads. 11

3. The method of regulating the magnetic strength of an electro-magnet, to adapt it to hold and release its armature at different loads, which consists in varying the strength of the current supplied to the magnet in 11 timed relation to and in strength proportioned to the respective loads.

4. The combination with an electro-magnetic clutch, of means for varying the electrical energy supplied to the clutch magnet 12 in timed relation to the operations of the clutch.

5. The combination, with an electro-magnetic clutch, of means for automatically varying the electrical energy supplied to 12 the magnet at different periods in the operation of the magnet, and in timed relation to those operations.

6. The combination, with an electro-magnetic clutch, of means for automatically varying the electrical energy supplied to the magnet for the periods at which the magnet engages and releases its armature.

7. The combination, with an electro-magnetic clutch, of means for varying the electrical energy supplied to the magnet in timed relation to its armature engaging and releasing periods, and in strength adapted to the working requirements of the magnet at those periods.

8. The combination, with an electro-magnetic clutch, of means for imparting a succession of movements to one of the clutch members, and means for supplying varying amounts of electrical energy to the magnet in timed relation to the movements of the clutch member.

9. The combination, with an electro-magnetic clutch, of means for imparting a succession of movements to one of the clutch members, and means for supplying varying amounts of electrical energy to the magnet member between the successive operations of the clutch.

10. The combination, with an electro-magnetic clutch, of means for imparting various amounts of electrical energy to the magnet member of the clutch, including an electric circuit, a rheostat in said circuit, an auxiliary circuit shunting the said rheostat, a second rheostat in the auxiliary circuit, and automatic means for opening and closing the auxiliary circuit.

11. The combination, with an electro-magnetic clutch, of means for imparting varying degrees of electrical energy to the clutch, including an electrical circuit, a rheostat in said circuit, an auxiliary circuit shunting the said rheostat, a second rheostat in the auxiliary circuit, and automatic means for opening and closing the auxiliary circuit in timed relation to the operations of the clutch.

12. The combination, with an electro-magnetic clutch, of a cam imparting a succession of movements to one of the members of the clutch, and means for varying the magnetic strength of the clutch during the said movements, including an electrical circuit connected with the magnet member, a rheostat in the said circuit, an auxiliary circuit shunting the said rheostat, and automatic means for periodically interrupting and restoring electrical communication in one of said circuits.

13. The combination with an electro-magnetic clutch, of a cam imparting a succession of movements to one of the members of the clutch, and means for varying the magnetic strength of the clutch during said movements, including an electrical circuit connected with the magnet member, a rheo-

stat in the said circuit, an auxiliary circuit 65 shunting the said rheostat, a second rheostat in the auxiliary circuit, and automatic means operating in timed relation to the said cam for opening and closing said auxiliary circuit.

14. The combination, with a machine element, of an armature operatively connected with the said element, a magnet member, means for imparting a prescribed movement to the magnet member, an electrical circuit 75 connected with the magnet, a rheostat in the said circuit, an auxiliary circuit shunting the said rheostat, a second rheostat in the said auxiliary circuit, and automatic means timed with the said moving means for opening and closing the auxiliary circuit.

15. The combination, with a magnet and its armature, of means for moving one of these members toward and from the other, and means timed with the said movements 85 for regulating the holding power of the magnet, giving it initial strength for seizing the armature, and then changing the power of the magnet to a predetermined releasing strength, whereby the magnet and the armature are separated upon meeting a predetermined resistance to their united movement.

16. The combination, with a magnet and its armature, of means for moving the magnet toward and from the armature, and means timed with said movements for imparting initial magnetic strength to the magnet for seizing the armature and for changing the strength of the magnet to a predetermined degree, whereby the magnet and armature are separated upon encountering a predetermined resistance to their united movement.

17. The combination of a magnet and its armature mounted for movement in a direction normal to their meeting surfaces, means for moving one of said parts in said direction, and means timed with the said movement for regulating the holding power of the magnet, increasing it to cause the said parts to seize and move together, and diminishing it during said movement, whereby the parts are separated upon encountering a predetermined resistance.

18. The combination of a magnet and its armature mounted for movement in a direction normal to their meeting surfaces, means for moving the magnet in the said direction toward and from the armature, and means timed with the said movements of the magnet for increasing the magnetic holding power of the magnet to cause the armature to seize and follow the magnet in its movement, and for lessening that magnetic strength to a predetermined extent to allow the parts to separate upon encountering a predetermined resistance.

19. The combination of a magnet and an

armature mounted for movement in a direction normal to their meeting surfaces, means for reciprocating the magnet toward and from the armature, and means timed with 5 the said reciprocating means for increasing the magnetic strength of the magnet to cause it to seize the armature when these parts are brought together, and for diminishing that

holding strength to a predetermined degree, whereby the armature is separated from the 10 magnet upon encountering a predetermined resistance to its movement.

Signed at Hartford, Connecticut, this 13th day of December, 1915.

KARL E. PEILER.
